UNITED STATES PATENT OFFICE.

WILLIAM F. HAUPT, OF ORANGE, NEW JERSEY, ASSIGNOR, BY MESNE ASSIGNMENTS, TO THE BATES MANUFACTURING COMPANY, OF ORANGE, NEW JERSEY, A CORPORATION OF NEW JERSEY.

NUMBERING MACHINE.

Application filed November 26, 1921. Serial No. 518,002.

To all whom it may concern:

Be it known that I, WILLIAM F. HAUPT, a citizen of the United States, and a resident of Orange, Essex County, New Jersey, have 5 invented certain new and useful Improvements in Numbering Machines, of which the following is a description.

This invention relates to numbering machines and more particularly to that class of 10 numbering machines which are automatic in their action, and which are usually made so that they may be set in order to permit a user to print numbers consecutively, or to duplicate the printing of numbers before the 15 machine automatically changes the units wheel, or to repeat by printing the same number over and over again. Machines of this character have also been designed and arranged so that they may be set to print a 20 number three, four, six, or any desired number of times, before automatically changing. The machine which is shown in the drawings accompanying this application is constructed and arranged so that it may be set 25 to repeat, to print consecutively, to duplicate, and to triplicate, the machine thus being capable of being set into four different adjusted positions and being what is known as a "four-movement" machine. The 30 machine shown, however, is also capable of further enlargement in the direction just noted and may also be arranged so that it has a less number of settings. As a matter of fact, the number of settings or combinations of 35 this character possible in a machine in accordance with my invention is practically unlimited, except by consideration of space and convenience.

Generally stated, the present invention resides in a numbering machine of this character of an improved construction and comprising fewer parts than are ordinarily used, so as to render the machine simpler, more compact, and more effective in operation.

45 One of the objects of my invention is to provide such a numbering machine with improved means for effecting the adjustments necessary to obtain the various settings, which are more effective and positive in operation and whereby the user may readily ascertain when the adjustment necessary to effect any desired setting is effected, this feature of my invention being especially applicable to numbering machines of the type

in which an indicator mounted for movement about a given axis is employed for making said adjustments. 55

Another object of my invention is to provide a machine of the character described with improved and simplified means for 60 more effectively and positively disengaging the usual stepped pawl, or equivalent device, from the numbering wheels and ratchet-wheels during the adjustment of the machine in effecting a change in the setting 65 thereof, and for holding the said stepped pawl or equivalent device, so disengaged when the machine is set for "repeat."

Further objects of my invention are to provide an improved mounting and arrangement for controlling and operating the usual ink pad frame in a machine of this character, and an improved and simplified construction for actuating the usual stepped pawl, or equivalent device, from the ink pad 75 frame upon the reciprocation of the numbering head of the machine.

Other objects and features of my invention will be hereinafter more specifically described. 80

Without in any way limiting myself to the particular machine illustrated, I may say that my invention consists in a numbering machine the preferable embodiment of which is hereinafter specifically described, and in 85 the combinations of elements and parts set forth in the appended claims.

In the drawings accompanying and forming a part of this application,

Figure 1 is a front elevation of one embodiment of my improved numbering machine;

Fig. 2 is a view similar to Fig. 1, partly in section, with the index plate and parts carried thereby removed;

Fig. 3 is a view in side elevation, partly 95 broken away, looking from the left in Fig. 1;

Fig. 4 is a view similar to Fig. 3 with the parts shown in the printing position;

Fig. 5 is an enlarged view in rear elevation of the index plate and the parts carried 100 thereby, and the shipper;

Fig. 6 is a perspective view of the shipper;

Fig. 7 is a perspective view of the numbering wheel barrel, one numbering wheel, one spacing washer, the stepped pawl, the governing ratchets or wheels, and certain of the operating parts associated with the barrel, some of the elements and parts being sepa-

rated and detached in order to show the arrangement and construction more clearly;

Fig. 8 is a plan view of one of the spacing washers used between the adjacent numbering and governing wheels;

Fig. 9 is a view in end elevation of the numbering wheel barrel with a single numbering wheel mounted thereon;

Fig. 10 is a view in perspective of the numbering machine head partly broken away, with the barrel, numbering and governing wheels and certain other parts omitted; and

Fig. 11 is a perspective view of the spring retarding pawl for the numbering and governing wheels.

The general construction of my improved numbering machine is quite similar to that shown in patent to Bates, No. 456,874, granted July 28, 1891. Referring to the drawings, reference character 1 represents the main frame of the machine which, as shown, is in the shape of an inverted U, the main operating mechanism being located between its legs. A plate 2 is suitably secured to the end of the legs of the frame 1 and is provided with an opening 3 through which the type of the numbering or type wheels project in printing or stamping the numbers, as indicated in Fig. 4, and at the edges of which the usual printing guides, not shown, are cut. At its top the frame 1 is provided with a collar 4 through which reciprocates the usual tubular spindle 5 of the numbering wheel head, such spindle having the usual handle 6 detachably connected to the upper end thereof. Within the tubular spindle 5 and the handle 6 is located a helical spring 7 which acts to normally hold the numbering head in the raised position shown in Figs. 1, 2 and 3, as is usual in this type of numbering machines. Below the helical spring 7 and extending through the collar 4 and spindle 5 is a pin 8 free to be moved transversely but having no vertical movement. The spindle 5 is slotted at 9, 9 to permit of its movement past the pin 8. One of the slots 9 is enlarged, as indicated at 10, at its upper end portion to about the size of the head of the pin 8, but this enlarged portion is not cut all the way through the material of the spindle, as shown in Figs. 1 and 2, and accordingly when the enlargement 10 in the downward movement of the spindle 5 is in alignment with pin 8, the head of the latter may be pushed into said enlargement, thereby locking the spindle together with the numbering wheel head and the parts carried thereby in depressed position. The numbering wheel head, indicated at 11, is in the form of a yoke or inverted U, and the sides or legs thereof are respectively provided with laterally extending pins 12 which slide in vertical guide-ways 13 in the legs of the main frame 1 to guide the numbering

head in its reciprocations. The type or numbering wheels 14, 15, 16, 17, 18, 19 and 20 are arranged side by side within the yoke 11, these wheels respectively being the usual units, tens, hundreds, thousands, tens of thousands, hundreds of thousands and millions wheels, or other suitable series of numbering wheels. The number of type or numbering wheels employed may, of course, be varied as desired. These numbering wheels are rotatably mounted upon a barrel 21 which fits between the depending side members of yoke 11 and is fixedly secured to said side members in a horizontal position as by means of screws, not shown, extending through the side members of the yoke and threaded into openings 22 provided in the ends of the barrel. A plurality of ring washers 23 are also mounted on the barrel 21, being respectively disposed between the adjacent numbering wheels. In order to prevent rotary movement of the washers 23, the barrel is provided with a small longitudinal recess 24 and each of the washers with an inward projection 25 conforming to and disposed in the recess 24. A spacing ring 26 is loosely mounted on the barrel 21 between the numbering wheel 20 of highest denomination and the adjacent side member of the yoke 11. Reference characters 27 and 28 respectively represent annular governing wheels or internal ratchets for controlling the duplicating and triplicating printing movements of the machine, these wheels being rotatably mounted on the barrel 21, in the order named, between the units wheel 14 and the adjacent right-hand side member of the yoke 11. Three of the washers 23 are also respectively disposed on the barrel 20 between the units wheel 14 and the governing wheel 27, between the governing wheels 27 and 28, and against the outer side of the wheel 28. One or more pilot pins 29 are suitably secured in the right-hand depending member or side of the yoke 11, as by being threaded thereinto, and project inwardly therefrom into engagement with the adjacent end member on the barrel 21, in this case the washer 23 disposed against the outer side of the governing wheel 28, to hold the wheel assembly against axial movement with respect to the barrel and spaced slightly from said right-hand side of the yoke.

Each of the numbering wheels, as is usual, is provided with nine (9) shallow notches 30 and one (1) deep notch 31 on the interior thereof, these notches being equi-spaced and having the usual disposition, i. e., there is one shallow notch 30 for each of nine numbers on the wheel, the deep notch or recess 31 being employed for the tenth number for the purpose of "carrying". The duplicate governing wheel 27 is provided on its interior with shallow notches 32 and

deep notches 33 alternately arranged, while the triplicate governing wheel 28 is provided on its interior with shallow notches 34 and deep notches 35 arranged so that every third notch is a deep notch 35. A shaft 36 is mounted in an axial opening extending through the barrel 21 for oscillatory and sliding movement, said shaft fitting quite closely within said opening and extending a considerable distance from each end of the barrel 21 and beyond the sides of the yoke 11 through openings 36' provided in said sides. Crank arms 37 are respectively secured intermediate their ends to the ends of the shaft 36 and outside the depending sides of the yoke 11, these crank arms being provided at one end with inwardly-extending pins 38 and being slotted at their other end as indicated at 39. Pawl means comprising a pawl bar 40 formed with a series of integral stepped pawls, is pivotally supported from and between the crank arms 37, said pawl bar being provided at its ends with aligned openings 41 with which the pins 38 on the crank arms 37 engage. The barrel 21 is provided with the usual longitudinal recess 42 receiving the pawl bar 40, said recess being of sufficient size to accommodate the pawl bar in the various positions it assumes in the operation of the machine. The washers 23 are each recessed at 43 opposite the recess 42 in the barrel 21, to accommodate the pawl bar 40 in its extreme outward movement. The openings 36' in the depending side members or legs of the yoke 11 are also of such size and shape as to accommodate the pawl bar 40 within the limits of its movements outwardly and inwardly. A small spring 44 is coiled about the pivot pin 38 of one of the crank arms 37 and bears at one end against said crank arm, while its other end bears against a pin 45 extending outwardly from one end of the pawl bar 40, the spring thus constantly acting to force the pawl bar outwardly about the pivot pins 38 and into coacting engagement with the notched interior peripheries of the anular numbering wheels and governing wheels 27 and 28.

When the machine is to be used for printing seven figures, that is, when there are seven type or numbering wheels, the pawl bar 40 comprises a series of eight pawls or teeth 46, 47, 48, 49, 50, 51, 52 and 53 of progressively decreasing length or height arranged in the usual stepped relation. The bar 40 is also provided with a single pawl or tooth 54 adjacent its right-hand end of substantially the same length as the adjacent longest pawl or tooth 46 of the series of stepped pawls, and with a deep notch 55 between the pawls or teeth 46 and 54, the notch 55 being slightly greater in width than the combined width of the governing wheels 27 and 28 and the washer 23 between the latter. When the numbering head 11 is reciprocated in the main frame 1, the shaft 36 and the pawl bar 40 carried thereby are oscillated to advance the numbering wheels by the usual step by step movements, it being understood, of course, that when the machine is set for "duplicate" or "triplicate", the pawl bar will be held from coacting with the numbering wheels except during every second or every third reciprocation of the head 11, while when the machine is set for "repeat", the pawl bar will be continuously held from coacting with the numbering wheels. This oscillatory movement is directly imparted to the shaft 36 and pawl bar 40 by a U-shaped ink pad frame 60 carrying the pad 61 for inking the type or numbers on the numbering wheels and pivotally supported from the yoke 11 by means of pivot screws or pins 63 which extend through the angular legs 62 of said frame and into the adjacent side members of the yoke. Above the pivots 63 the legs 62 of the ink pad frame are provided with pins 64 which respectively directly engage the slots 39 of the crank arms 37 on the ends of the shaft 36, and below the pivots 63 at or adjacent their angle or bend, these legs are respectively provided with like slots 65 which are respectively slidably engaged by the reduced smooth end portions of screws 66 extending inwardly from the legs of the main frame 1. The arrangement is such that as the numbering head 11 is reciprocated in the main frame 1, the pins or screws 66 coact with the slots 65 to effect movement of the ink pad frame about the axis of pivots 63, this frame in the down movement of the numbering head being moved outwardly about the pivots 63 to that position in which the ink pad 61 is most remote from the numbering wheels, as shown in Fig. 4, and being moved inwardly about the pivots 63 to the position shown in Figs. 1, 2 and 3 with the pad 61 pressed firmly against the type of the numbering wheels which are to make the next printing impression, on the up movement of said numbering head. In such pivotal movement of the ink pad frame the pins 64 carried by the legs 62 thereof directly coact with the slots 39 of the crank arms 37 to oscillate the latter and thereby the shaft 36 and pawl bar 40, the arrangement being such that the oscillatory movement thus imparted to the pawl bar is slightly greater than that necessary to advance through one step, the wheel or wheels with which a pawl or pawls of the pawl bar may, at the moment, engage.

The pawl bar 40 has four transverse operative positions with respect to the numbering wheels and the governing wheels, re-

4

spectively corresponding to the four settings, namely, "consecutive," "duplicate," "triplicate" and "repeat," of the specific form of my improved numbering machine shown and described herein. In the operative position of the pawl bar corresponding to the "consecutive" setting of the machine, the pawls 46, 47, 48, 49, 50, 51 and 52 will be respectively opposite the numbering wheels 14, 15, 16, 17, 18, 19 and 20 for coaction therewith; and with the pawl bar in this operative position and the other parts of the machine properly adjusted for the "triplicate" setting, the duplicate governing wheel 27 will not function due to the fact that the deep notch 55 of the bar is opposite such wheel, but the triplicate governing wheel 28 will function, and upon each reciprocation of the numbering head the said wheel 28 will be advanced one step by the pawl 54, and as will be understood, the stepped pawls of the bar 40 will be operative to effect the advance of the proper numbering wheel or wheels only when said pawl 54 lies in one of the deep notches 35 of the wheel 28, that is, only upon every third reciprocation of the numbering head, the result being that any number will be printed three times or triplicated before changing to the next number. The operative position of the pawl bar corresponding with the "repeat" setting of the machine will be identical with its operative position for the "consecutive" setting of the machine; and with the pawl bar in this operative position and the other parts of the machine properly positioned for the "repeat" setting, the pawl bar will be held, by means presently to be described, in a position in which none of its pawls engage or coat with any of the numbering and governing wheels, so that upon successive reciprocations of the numbering head the same number will be printed over and over again.

An index plate 70, provided with a scale comprising suitable indications of the various settings of the machine, is secured, as by means of screws 71, to the front of the numbering head 11, and an indicator or pointer 72 cooperating with said scale, is mounted by means of pin 73, for pivotal movement about an axis fixed with respect to the plate 70 and adjacent the center thereof. To change the setting of the machine it is merely necessary to move the indicator 72 over the scale on the index plate and in either direction about its pivotal axis to the indication corresponding to the desired setting. In changing the setting of the machine it is important that the pawl bar be first moved to wholly disengage its pawls from all the numbering and governing wheels without any accompanying transverse movement of the bar, that with said pawl bar in disengaged position, the same then be moved transversely of the numbering and governing wheels to the operative position corresponding to the desired setting of the machine, and that the pawl bar 125 then be moved to engage the proper pawl or pawls thereof with one or more of the numbering and governing wheels without any concurrent transverse movement of said bar. If these movements of the pawl bar 130

are thus effected, all binding and rubbing which would otherwise result by reason of the engagement of the numbering and governing wheels by the pawls of the pawl bar 5 in the transverse movements of the latter, are wholly eliminated. In my improved machine I provide simple and effective means for correctly and properly effecting and timing such movements of the pawl bar 10 when changing the setting of the machine, the construction and operation of which, when viewing the machine from the front, will now be described. The means for moving the shaft 36 and thereby the pawl bar 15 40 into its various transverse operative positions with respect to the numbering and governing wheels, includes a shipper comprising a plate 74 having an enlarged rectangular central portion provided with an 20 opening 75, the latter having parallel vertical side edges or walls and being generally rectangular in shape. The plate 74 is provided with arms 76 extending laterally from its enlarged central portion, and is mounted 25 on the numbering head or yoke 11, just to the rear of the index plate 70, for sliding movement in a horizontal direction, the arms 76 thereof being received in recesses 77 formed in the front edges of the side members 30 of the yoke. The arms 76 of the shipper are respectively provided with rearward extensions 77 embracing the yoke 11, said extensions being parallel and spaced apart a distance considerably in excess of the 35 width of the yoke. At their rear ends the extensions 77 are provided with flat vertical portions 78 extending outwardly therefrom at right angles, these vertical portions respectively loosely engaging the vertical 40 guide-ways 13 in the legs of the main frame 1. The right angular vertical portions 78 of the extensions 77 are provided with inwardly directed lower end portions 79 which embrace and lie closely adjacent the crank arms 87 on the ends of the shaft 36. It will thus be apparent that transverse movement of the shipper with respect to the numbering head or yoke 11 will effect a like movement of the shaft 36 and pawl bar 40. The 45 pivot pin 73 for the indicator 72 is journaled in the index plate 70 and extends rearwardly through this plate and through the opening 75 in the shipper plate 74 substantially at the center of said opening. A cam 50 80 of peculiar shape is attached to the pivot pin 73 and is disposed within the opening 75 of the shipper plate, this cam being so formed that in all angular positions thereof it will engage both side walls or edges of the said opening and will be free from engagement with the top and bottom walls or edges thereof. It will thus be apparent that all transverse movements of the shipper, shaft 36 and pawl bar 40 resulting from movement of the indicator 72 and 55 cam 80, will be positively effected. The edge of the cam 80 is provided with four high portions or points 81, 81, 82 and 83; the points 81, 81 being diametrically opposite and equidistant from the axis of the pivot 70 pin 73, the point 82 being at a less distance from the axis of pivot pin 73 than points 81, 81, and the point 83 being diametrically opposite the point 82 and at a greater distance from the axis of pivot pin 73 than the points 81, 81. These high portions or 60 points on the edge of cam 80 are preferably angularly spaced 90° apart with reference to the axis of pivot pin 73. When the cam 80 is moved by the pointer 72 to the position shown, with its high points 81, 81 respectively engaging the opposite side walls or edges of the opening 75 in the shipper, the latter will be moved to its median position and will thereby effect endwise movement 65 of the shaft 36 and the pawl bar 40 to position the latter in its transverse operative position corresponding to the "consecutive" setting of the machine. The indicator 72 will then point to the "consecutive" indication on the scale of the index plate 70. If the indicator 72 is now moved to the left about its pivotal axis to the "duplicate" indication, the cam 80 will be moved through an angle of 90° to bring the high point 82 70 thereof against the left-hand side wall or edge of the opening 75 and the high point 83 thereof against the right-hand side wall or edge of said opening; and such movement of the cam will effect movement of 75 the shipper and thereby of the shaft 36 and pawl bar 40 to the right to bring the latter into its transverse operative position corresponding to the "duplicate" setting of the machine. Pivotal movement of the indicator 72 to the right from the "consecutive" indication to the "triplicate" indication will, of course, move the cam 80 through an angle of 90° in a clock-wise direction, and will bring its high point 82 into engagement 80 with the right-hand side wall or edge of the opening 75 in the shipper and its high point 83 into engagement with the left-hand side wall or edge of said opening; and such movement of the cam will effect movement of 85 the shipper and thereby of the shaft 36 and pawl bar 40 to the left to bring the latter into its transverse operative position corresponding to the "triplicate" setting of the machine. If the indicator 72 is moved from 90 the "consecutive" indication to the "repeat" indication, the cam 80 will be moved through an angle of 180°, and while the shipper, shaft 36 and pawl bar 40 will be moved transversely during such movements of the 95 indicator 72 and cam 80, the final transverse positions of said shipper, shaft and pawl bar, that is, their positions when the indicator reaches the "repeat" indication, will be the same as they were in when the indicator 100 105 110 115 120 125 130

6

cator was at the "consecutive" indication. The positions of the two diametrically opposite high points 81, 81 of the cam, however, will be reversed, as will also the positions of the two diametrically opposite high points 82 and 83. The pawl bar 40 will now be in its transverse operative position corresponding to the "repeat" setting of the machine. Secured to the pivot pin 73 10 between the shipper plate 74 and the index plate 70 is a second cam 85 in the form of a plate which is generally circular in shape but which is provided with three deep notches 86, 87 and 88 and a shallow notch 89 spaced 90° apart. Reference character 15 90 represents a lever, formed from a thin flat piece of metal, which is mounted at one end by a pin 91 on the rear side of index plate 70, for movement between the latter 20 and the shipper 74 about the axis of said pin. The other end of the lever 90 is provided with a right angular rearwardly-extending portion 92 having a slot 93 therein. Intermediate its ends the lever 90 is 25 provided with an upwardly-extending rounded nib 94 engaging the edge of the cam 85 and adapted to coact with the notches 86, 87, 88 and 89 therein as will presently appear. A strong spring 95 secured at one 30 end to the lever 90 and at its other end to the index plate 70 tends to force the lever upwardly about the pivot pin 91 and maintains the nib 94 in engagement with the edge of the cam 85 under a firm but yielding pressure. An elongated thin segmental member 96 is mounted in the narrow space between the right-hand end of the wheel assembly on the barrel 21 and the right-hand side of the yoke 11, for movement towards 35 40 and from the axis of said barrel, so as to control the engagement of the pawls of the pawl bar with the notched interior peripheries of the numbering and governing wheels. Preferably, the member 96 is 45 mounted on the inner side of the right-hand side of the yoke by means of one of the pilot pins 29 and a pin 99 carried by said side which respectively engage slots 97 and 98 provided in the end portions of said member. Member 96 is provided at a point considerably below its center but above the slot 97, with an inwardly-extending pin 100, and this pin is in engagement with the slot 93 50 in the end portion 92 of lever 90. It will 55 therefore be apparent that movements of the lever 90 upwardly and downwardly about its pivot 91 will respectively effect movements of the member 96 towards and from the axis of barrel 21. The position 60 of pin 100 and the shape and arrangement of the slots 97 and 98 are such that member 96, when actuated by lever 90, will slide on both the pins 29 and 99 and will also move about the upper pin 99, that is, a combined sliding and pivotal movement will 65 thus be imparted to this member. The inner curved edge of member 96 is adapted to engage the adjacent end portion of the pawl bar 40 at its outer extremity, and when said member is moved towards the axis of barrel 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 on the index plate 70. It will therefore be apparent that the cam 85 and spring-pressed lever 90 will coat, by reason of the engagement of the nib 94 of the lever with the notches in the cam, to yieldingly lock the various parts in their adjusted positions for the different settings of the machine. It will also be obvious that I have provided unitary means, including but a single member 5 acting on the pawl bar 40, viz., the slidably and pivotally mounted member 96, for controlling the engagement of the pawl bar 40 with the numbering and governing wheels and for holding or locking said bar 10 in its disengaged position with respect to said wheels when the machine is set for "repeat". Each of the high portions 81, 81, 82 and 83 on the edge of cam 80, is circular and on an arc, the center of which 15 lies in the axis of the pin 73 to which the indicator 72 and cams 80 and 85 are secured, and the length of these high circular portions and the relative angular positions of cams 80 and 85 are such, that during such 20 angular movement of the indicator 72, pin 73 and cam 85 as is necessary either to effect the disengagement of the nib 94 on lever 90 from any of the notches 86, 87, 88 and 89 and the engagement of the nib with one of 25 the circular edge portions of the cam 85 at a point closely adjacent such notch, or to effect the disengagement of said nib from such a point on a circular edge portion of cam 85 and the seating thereof in the adjacent notch, 30 no transverse movement whatever will be imparted to the shipper 74, shaft 36 and pawl bar 40 by the cam 80. Accordingly, upon moving the indicator 72 from one indication on index plate 70 to the next indication to change the setting of the machine, the various operations for effecting such change in setting will be accomplished in the desired sequence, that is, the pawl bar will be first disengaged from the wheels 35 on barrel 21 while the shipper, shaft 36 and pawl bar are held against transverse movement; the shipper, shaft 36 and pawl bar will then be moved transversely to bring the pawl bar into its transverse operative position corresponding with the desired setting 40 while the pawl bar is maintained disengaged from the wheels, and then while the shipper, shaft 36 and pawl bar 40 are held against transverse movement the pawl bar will be moved into engagement with the wheels or, 45 in the case of the "repeat" setting, will be yieldingly locked in disengaged position. With the construction and arrangement described, it will be apparent that the setting 50 of the machine may be changed merely by moving the indicator 72 in either direction from any indication on the scale of the index plate 70 to the indication of the desired setting. 55 As has previously been mentioned, the pawl bar 40 is oscillated by the link pad frame 60, in each reciprocation of the numbering head 11, through an angle slightly greater than that necessary to advance one step the wheel or wheels which may be engaged by a pawl or pawls of said bar. Accordingly, in any advance movement of each numbering wheel, the same is moved forward through an angle slightly greater than that necessary to align the next numeral 70 thereof to be printed with the corresponding numerals of the other numbering wheels. Means is therefore provided for automatically and exactly aligning the numerals of 75 all the numbering wheels in each downward movement of the numbering head and preferably just before the wheels reach the printing position. As shown, this means comprises a horizontal rod or shaft 105 pivotally mounted in the side members of the numbering head 11, to which is suitably secured within the numbering head, a thin resilient depending apron 106, preferably formed of sheet metal. The lower end 107 of apron 106 is directed inwardly and is 80 adapted to engage tapered recesses formed in the outer peripheries of the numbering wheels between the numerals. At one end the rod or shaft 105 is provided with a rearwardly-extending arm 108, the end portion of which in the latter part of the downward movement of the numbering head, is engaged by a pin 109 secured to one of the legs of the main frame 1, as shown in Fig. 4. Such 85 engagement of the arm 108 with the pin 109 effects pivotal movement of said arm and the shaft 105, and thereby moves the apron 106 towards the numbering wheels to bring the lower end 107 thereof into one of the tapered recesses on the outer periphery of 90 each of the numbering wheels, said end 107 then coacting with the walls of said recesses so as to move the wheels to accurately align the numerals and to hold them so aligned 95 during the printing operation. On the upward movement of the numbering head the rod 105 together with the apron 106 and arm 108, will return under the action of gravity, to the position shown in Fig. 3. 100

In addition to the longitudinal recesses 24 and 42, the barrel 21 is also provided with a longitudinal U-shaped recess 110, preferably substantially diametrically opposite the recess 42. In the recess 110 is disposed suitable pawl retaining means adapted to 105 coact with the interior notched peripheries of the numbering and governing wheels to prevent rearward movement of the wheels and also to prevent the wheels from being too easily advanced. The pawl retaining means which I employ is of a simple and improved construction and preferably comprises a single resilient sheet metal member 111 substantially U-shaped in cross-section, one side or leg 111' of which is longer than the other, 110

125

130

and the length of which is substantially the same as that of the wheel assembly. The short side of the member 111 is slit so as to provide the same with spring fingers 112 corresponding in number to the numbering wheels and governing wheels of the wheel assembly. The member 111 is set in the recess 110 so that the curved base thereof closely engages the bottom of the recess. The 10 upper solid portion of the longer side 111' of member 111 is provided with a plurality of circular openings 113, these openings being respectively engaged by the end portions of cylindrical pins 114 mounted in the barrel 21 and extending into the recess 110. The openings 113 are somewhat larger in diameter than the extending end portions of pins 114, and the construction is such that when the member 111 is properly disposed in the recess, the base portions of said member and the wall of said recess will contact so that the walls of openings 113 will be frictionally engaged, at their inner sides, with pins 114 under the resiliency of said 20 member and the latter thus firmly but removably held within the recess in the position shown in Fig. 9. This construction permits of easy removal of the member 111 from the recess 110 of the barrel 21, when the numbering and governing wheels have 30 been dismounted therefrom, by merely pressing the longer side or leg 111' thereof away from the adjacent wall of recess 110 until the openings 113 disengage pins 114. The 35 fingers 112 tend under their resiliency, to assume a position with their outer ends somewhat beyond the inner peripheries of the numbering and governing wheels, as indicated in Fig. 9, and accordingly when the 40 wheels are mounted on the barrel, these fingers always press against the inner peripheries of said wheels and will spring into engagement with any of the notches in the said peripheries which are registered therewith.

It is to be understood that certain of the features of my invention are capable of application to numbering machines of various types, and also that while I have shown and described a preferred form of my improved numbering machine, such machine is subject to numerous modifications and changes in the size, shape and arrangement of parts without departure from the spirit 50 of my invention or the scope of the appended claims.

Having now described my invention, what I claim as new and desire to protect by Letters Patent is as follows:

60 1. In a numbering machine, a series of numbering wheels, pawl means adapted to coact with said wheels in a number of transverse operative positions with respect to the wheels, a pivoted indicator, and means 65 whereby pivotal movement of said indicator

will first move said pawl means out of coacting position with respect to said wheels and will then move the pawl means transversely to another operative position, substantially as described. 70

2. In a numbering machine, a series of numbering wheels, pawl means adapted to coact with said wheels in a number of transverse operative positions with respect to the wheels, a movable indicator, and means 75 whereby movement of said indicator in a given direction will first move said pawl means out of coacting position with respect to said wheels and will then move the pawl means transversely to another operative 80 position, substantially as described.

3. In a numbering machine, a series of numbering wheels, pawl means adapted to coact with said wheels and movable transversely thereof to a number of operative 85 positions with respect to the wheels, a pivoted indicator, and means whereby pivotal movement of said indicator in either direction will first move said pawl means out of coacting position with respect to said wheels 90 and will then move the pawl means transversely to another operative position, substantially as described.

4. In a numbering machine, a series of numbering wheels, pawl means adapted to 95 engage said wheels in a number of transverse operative positions with respect to the wheels, a member movable to control the engagement of said pawl means with said wheels, a shipper adapted to move said pawl means transversely of said wheels to its different operative positions, an indicator, and means actuated by said indicator upon movement thereof comprising a pair of elements 100 respectively cooperating with said member and shipper, said elements being so arranged with respect to said member and shipper that upon movement of the indicator from a given position said member will first be 105 actuated to disengage the pawl means from said wheels and said shipper will then be actuated to move said pawl means transversely of said wheels, substantially as described. 110

5. In a numbering machine, a series of 115 numbering wheels, pawl means adapted to engage said wheels in a number of transverse operative positions with respect to the wheels, a member movable to control the engagement of said pawl means with said wheels, a shipper adapted to move said pawl means transversely of said wheels to its different operative positions, a pivoted indicator, and two cams secured to said indicator and respectively cooperating with said member and shipper to control the operation thereof, substantially as described. 125

6. In a numbering machine, a series of 130 numbering wheels, pawl means adapted to engage said wheels in a number of trans-

verse operative positions with respect to the wheels, a member movable to control the engagement of said pawl means with said wheels, a shipper adapted to move said pawl means transversely of said wheels to its different operative positions, a pivoted indicator, and two cams secured to said indicator and respectively cooperating with said member and shipper to control the operation thereof, said cams being so shaped that upon pivotal movement of said indicator from a given position said member will first be actuated to disengage the pawl means from said wheels and said shipper will then be actuated to move said pawl means transversely of the wheels, substantially as described.

7. In a numbering machine, a numbering head, a series of numbering wheels carried by said head, pawl means adapted to coact with said wheels, a movable indicator, and means actuated by said indicator for controlling the engagement of the pawl means with said wheels, said means comprising a member slidably mounted on said numbering head for movement towards and from said pawl means, substantially as described.

8. In a numbering machine, a numbering head, a series of numbering wheels carried by said head, pawl means adapted to coact with said wheels, a movable indicator, and means whereby movement of said indicator controls the engagement of said pawl means with said wheels, said means comprising a member slidably mounted on said numbering head for movement towards and from said pawl means and cooperating elements for yieldingly locking said slideable member in a position holding said pawl means out of engagement with said wheels upon movement of said indicator to a predetermined position, substantially as described.

9. In a numbering machine, a numbering head, a series of numbering wheels carried by said head, pawl means adapted to coact with said wheels, a movable indicator, and means actuated by said indicator for controlling the engagement of the pawl means with said wheels, said means comprising a member mounted on said numbering head for sliding and pivotal movement towards and away from said pawl means, substantially as described.

10. In a numbering machine, a numbering head, a series of numbering wheels carried by said head, a pawl means adapted to coact with said wheels, a movable indicator, and means whereby movement of said indicator controls the engagement of said pawl means with said wheels, said means comprising a member mounted on said head for sliding and pivotal movement towards and from said pawl means and cooperating elements for yieldingly locking said member in a position holding said pawl means out of en-

gagement with said wheels upon movement of said indicator to a predetermined position, substantially as described.

11. In a numbering machine, a main frame, a numbering wheel head mounted for reciprocation in said main frame and carrying a series of numbering wheels, and an ink pad frame pivoted on said numbering head, said ink pad frame having pin and slot connection with said main frame whereby such ink pad frame will be properly moved to and from operative position upon reciprocation of the numbering wheel head, substantially as described.

12. In a numbering machine, a main frame, a numbering wheel head mounted for reciprocation in said main frame and carrying a series of numbering wheels, pawl means adapted to coact with said wheels, a movably mounted support for said pawl means, and an ink pad frame arranged to be automatically moved to and from operative position with respect to said wheels upon reciprocation of said numbering wheel head, said ink pad frame having a direct connection with said pawl means support to actuate the latter and thereby the pawl means, substantially as described.

13. In a numbering machine, a series of numbering wheels, pawl means adapted to engage said wheels in a number of transverse operative positions with respect to the wheels, a pivoted indicator, means for moving said pawl means to each of its transverse operative positions by pivotal movement of said indicator, and means operative by the pivotal movement of the indicator for controlling the engagement of the pawl means with said wheels, substantially as described.

14. In a numbering machine, a series of numbering wheels, pawl means adapted to engage said wheels in a number of transverse operative positions with respect to the wheels, a pivoted indicator, means for moving said pawl means to each of its transverse operative positions by pivotal movement of said indicator, and means controlled by the pivotal movement of the indicator for locking the pawl means in said operative positions, substantially as described.

15. In a numbering machine, a series of numbering wheels, pawl means adapted to engage said wheels in a number of transverse operative positions with respect to the wheels, a pivoted indicator, means for moving said pawl means to each of its transverse operative positions by pivotal movement of said indicator, and means controlled by the pivotal movement of the indicator for disengaging the pawl means from said wheels and for locking the pawl means so disengaged in one of its transverse operative positions, substantially as described.

16. In a numbering machine, a series of

numbering wheels, pawl means adapted to engage said wheels in a number of transverse operative positions with respect to the wheels, a pivoted indicator, means for moving said pawl means to each of its transverse operative positions by pivotal movement of said indicator, and means operative by the pivotal movement of the indicator for controlling the engagement of the pawl means 10 with said wheels and for locking the pawl means in said operative positions, substantially as described.

17. In a numbering machine, a series of 15 numbering wheels, pawl means adapted to engage said wheels in a number of transverse operative positions with respect to the wheels, a pivoted indicator, means for moving said pawl means to each of its transverse operative positions by pivotal movement of 20 said indicator, and means controlled by the pivotal movement of the indicator for disengaging the pawl means from said wheels, for locking the pawl means so disengaged in one of its transverse operative positions, and for 25 locking the pawl means in said operative positions, substantially as described.

18. In a numbering machine, a main 30 frame, a numbering wheel head mounted for up and down movement in said main frame and carrying a series of numbering wheels, 35 pawl means adapted to advance said wheels, and an ink pad frame pivotally supported on said numbering head and having direct pin and slot connection with said main frame whereby said ink pad frame will be moved respectively toward and away from the numbering wheels upon the up and down movements of the numbering head, said ink pad frame also having connection with 40 said pawl means to actuate the latter, substantially as described.

19. In a numbering machine, a main 45 frame, a numbering wheel head mounted for up and down movement in said main frame and carrying a series of numbering wheels, 50 pawl means adapted to advance said wheels, and an ink pad frame pivotally supported on said numbering head and having direct pin and slot connection with said main frame whereby said ink pad frame will be moved respectively toward and away from the numbering wheels upon the up and down movements of the numbering head, said ink pad frame also having direct pin and slot 55 connection with said pawl means to actuate the latter, substantially as described.

20. In a numbering machine, a main 60 frame, a numbering wheel head mounted for reciprocation in said main frame and carrying a series of numbering wheels, pawl 65 means adapted to coact with said wheels, a movably mounted support for said pawl means, and an ink pad frame arranged to be automatically moved to and from operative 70 position with respect to said wheels.

upon reciprocation of said numbering wheel head, said ink pad frame having a direct pin and slot connection with said pawl means support to actuate the latter and thereby the pawl means, substantially as described. 70

21. In a numbering machine, a wheel 75 barrel on which a plurality of annular wheels are adapted to be rotatably mounted, and pawl retaining means for said wheels comprising a resilient member, said member being mounted on said barrel and firmly held thereon under its own resiliency, substantially as described.

22. In a numbering machine, a wheel 80 support, a series of wheels rotatably mounted on said support and adapted to be advanced with a rotary step by step movement, and pawl retaining means for said wheels comprising a plurality of pawls adapted to cooperate with the respective 85 wheels carried by a resilient support, said pawl retaining means being firmly and removably secured to the wheel support under the resiliency of its resilient support, substantially as described. 90

23. In a numbering machine, a wheel 95 barrel on which a plurality of annular wheels are adapted to be rotatably mounted, said barrel having a recess and means projecting into said recess, and pawl retaining 100 means for said wheels comprising a resilient member, said member being disposed in said recess and cooperating with the wall thereof and said projecting means so as to be firmly secured to the barrel under its own resiliency, substantially as described.

24. In a numbering machine, a barrel on 105 which a plurality of annular wheels are adapted to be rotatably mounted, said barrel having a substantially U-shaped recess and pins projecting into the latter, and pawl retaining means for said wheels comprising a substantially U-shaped resilient member having a plurality of openings in one side or leg and disposed in said recess with said openings respectively engaged by said pins, said member coacting with the wall of said recess to maintain the walls of said openings at one side thereof in frictional engagement with said pins under its resilient action, such member thereby being firmly and removably held in said recess, substantially as described. 110

25. In a numbering machine, a series of 115 annular numbering wheels and a pair of adjacent annular governing wheels, said wheels being coaxially mounted and having notched inner peripheries, a pawl bar 120 mounted within said wheels and movable transversely with respect thereto, said bar being provided with stepped pawls for coaction with the numbering wheels, a pair of pawls respectively adapted to cooperate with said governing wheels and a notch 125 between said last pawls of a width suffi- 130

cient to accommodate both of said governing wheels, and means for moving said pawl bar to a position in which said notch is opposite both said governing wheels and to 5 positions in which one or the other of said pair of pawls is opposite the respective governing wheel with which it is adapted to cooperate, substantially as described.

26. In a numbering machine, a series of 10 annular numbering wheels, a plurality of annular governing wheels, and a pawl bar mounted within said wheels and movable transversely with respect thereto, said bar being provided with stepped pawls for 15 coaction with the numbering wheels and with portions adapted to cooperate with said governing wheels, said pawl bar being movable to an intermediate position in which none of said portions is opposite any of said 20 governing wheels and to transverse positions to either side of said intermediate position and in each of which transverse positions one of said portions is opposite one of the governing wheels, substantially as de- 25 scribed.

27. In a numbering machine, a series of annular numbering wheels, a plurality of adjacent annular governing wheels, and a pawl bar mounted within said wheels and 30 movable transversely with respect thereto, said bar being provided with stepped pawls for coaction with the numbering wheels, portions adapted to cooperate with said governing wheels and a notch between said 35 portions of a width sufficient to accommodate said governing wheels, said pawl bar being movable to a position in which said notch is opposite all said governing wheels and to other positions in which one or the 40 other of said portions is opposite a governing wheel, substantially as described.

28. In a numbering machine, a series of annular numbering wheels, annular governing means, and a pawl bar mounted within 45 said wheels and governing means and movable transversely with respect thereto, said bar being provided with stepped pawls for coaction with the numbering wheels, portions adapted to cooperate with said governing 50 means and a notch between said portions of a width sufficient to accommodate said governing means, said pawl bar being movable to a position in which said notch is opposite said governing means and to 55 other positions in which one or the other of

said portions is opposite the governing means, substantially as described.

29. In a numbering machine, a series of annular numbering wheels, annular governing means, and a pawl bar mounted within 60 said wheels and governing means and movable transversely with respect thereto, said pawl bar being provided with stepped pawls for coaction with the numbering wheels and with portions adapted to cooperate with 65 said governing means, said pawl bar being movable to an intermediate position in which none of said portions is opposite the governing means and to transverse positions to either side of said intermediate 70 position and in each of which transverse positions one or another of said portions is opposite said governing means, substantially as described.

30. In a numbering machine, a plurality 75 of numbering wheels, a plurality of governing wheels, and a pawl bar movable transversely with respect to said wheels, said bar being provided with stepped pawls for coaction with the numbering wheels and with portions adapted to cooperate with 80 said governing wheels, said pawl bar being movable to an intermediate position in which none of said portions is opposite any of said governing wheels and to transverse positions 85 to either side of said intermediate position and in each of which transverse position one or another of said portions is opposite one of the governing wheels, substantially as de- 90 scribed.

31. In a numbering machine, a series of numbering wheels, governing means, a pawl bar mounted for movement transversely with respect to said wheels and governing means, said bar being provided 95 with stepped pawls for coaction with the numbering wheels and with portions adapted to cooperate with said governing means, said pawl bar being movable to an intermediate position in which none of said portions is opposite said governing means and to transverse positions to either side of said intermediate position and in each of which transverse positions one or another of said portions is opposite said governing means, substantially as described.

This specification signed this 19th day of November, 1921.

WILLIAM F. HAUPT.
